UNITED STATES PATENT OFFICE.

ANDERSON CARTWRIGHT HECK, OF FINDLAY, OHIO.

SECTIONAL CONVEYER-FRAME FOR EXCAVATING-MACHINES.

No. 883,016.

Specification of Letters Patent. Patented March 24, 1908.

Application filed May 27, 1907. Serial No. 375,928.

To all whom it may concern:

Be it known that I, ANDERSON CARTWRIGHT HECK, a citizen of the United States, residing at Findlay, in the county of Hancock and State of Ohio, have invented certain new and useful Improvements in Sectional Conveyer-Frames for Excavating-Machines; and I do hereby declare the following to be a full, clear, and exact description of the invention, such as will enable others skilled in the art to which it appertains to make and use the same.

This invention relates to conveyers for excavating machines, and is particularly designed for use with ditching machines providing a large revoluble hollow ditching wheel within which is located a transversely-disposed conveyer for carrying the dirt projected thereon, by the buckets of the ditching wheel, transversely of the ditch being cut. And it is very desirable in a machine of this character to provide said transverse conveyer in some way with suitable means for elevating and lowering the frame to make the discharge end assume different angles of position for various purposes, for instance in order to allow the outer end of the conveyer to be kept from interfering with the waste bank, also to allow the part under and within the wheel to remain stationary and level for the discharge of dirt thereon. It may also be serviceable in avoiding obstructions met with in the digging of a ditch across rough ground.

In conveyers as at present employed, the conveying apron, where adjustably supported at all, is carried by a rigid frame pivotally connected to the framework of the excavating machine, the entire conveyer frame swinging on its pivot, a construction which has been found to be more or less disadvantageous, and one of the objects of the present invention is to provide the frame for the conveying apron in the form of a sectional frame, the sections of which are pivotally secured together, and one section being adapted to be rigidly secured to the machine, the remainder of the conveyer being adapted to be raised or lowered, as occasion may require. At the same time these sections are provided with suitable sprocket wheels and rollers co-operating with sprocket chains secured to the apron, and so related that when the movable part of the frame is not in a straight position the apron will still freely move, although one

portion of the same is at a different angle 55 from the other.

Another object of the invention is to provide what I have termed a hopper at the receiving end or stationary part of the conveyer frame provided with sides of flexible material, 60 such as canvas or similar fabric, or rubber strips, disposed to project in engagement with the apron and prevent the lateral discharge therefrom of any dirt or other particles onto the sprocket wheels or other parts of 65 the running mechanism. This is particularly desirable at this position of the conveyer where the buckets are discharged and where there is more or less jolting of the materials.

While I do not restrict myself to the exact 70 details shown and described, still for the purpose of disclosure, reference is had to the accompanying drawings illustrating a practical embodiment of the invention, in which—

Figure 1 designates a view in side elevation of my conveyer frame and hopper disassociated from an excavating machine, and showing in dotted lines the movable part of the frame elevated, and also showing one of the end shafts in section with the outer 75 sprocket wheel, omitted for clearness of illustration. Fig. 2 is a plan view of same, and Fig. 3 is a cross section through the stationary part of the frame on the line 3—3 of Fig. 2, looking in the direction of the arrows, and 80 also showing the endless apron in section.

The conveyer frame is formed of a plurality of pivotally connected sections, forming a sectional frame, one part of which is adapted to be rigidly secured to the machine 90 and hereinafter referred to as the stationary part 1, and the other part of which is movable vertically, and is hereinafter referred to as the movable part 2. These two parts consist of hollow frames, the stationary part 95 comprising sides 3; which may be in the form of channeled I-beams, tied together by the tie-rods 4. This frame or stationary part is adapted to be securely fixed to the framework of the excavating machine, and is provided at one end with the bearing lugs 5, and at the other end with the rotatable shaft 6 carrying the sprocket wheels 7, the guide wheels 8, and an end sprocket wheel 9. The bearing lugs 5 may be of any suitable construction, and are simply shown on the drawings as being short sections bolted on 100 the vertical web of the I-beam.

The movable part, illustrated for simplicity as comprising a longer frame, is substantially the same in construction, and comprises the side beams 10, cross tie rods 11, and is provided at its outer end with the bearing brackets 12 journaling a rotatable shaft 13 carrying sprocket wheels 7, guiding wheels 8, and an end sprocket wheel 9 similar to that referred to in connection with the stationary part. This movable part is also provided with bearing lugs 5, and through these lugs, which are arranged in alinement, is passed a loosely-mounted shaft 14 carrying guiding rollers 15.

Disposed transversely of and journaled within the sectional members are a plurality of guiding rollers 16 for supporting the conveyer apron. Also disposed along same, on both sides thereof, are a plurality of idle sprocket wheels 17, disposed in alinement with the sprocket wheel 7 and adapted to mesh with sprocket chains, shown in dotted lines in Fig. 1, as at 18, which sprocket chains are suitably secured to the inside faces of the endless apron. The dotted line at 19, in Fig. 2, designates a driving chain meshing with the end sprocket wheels 9, and this chain may be driven by a suitable sprocket, shown in dotted lines at 20, which may be carried on a shaft 21, mounted on the machine proper, and which shaft may pass through the journal opening 22 (Fig. 1) formed on the I-beam.

As shown more clearly in Fig. 3, 23 designates brackets secured to the side beams 3 on the stationary part and bent and disposed upwardly thereof. These brackets, at their upper ends, support a three sided frame 24, provided with flexible sides 25 of any suitable material, such as a rubber strip, canvas, or the like, which flexible walls, at their lower ends, are adapted to engage the apron 26, and prevent the discharge laterally of any dirt therefrom at the position where the material is dumped on the apron.

As above stated, my conveyer is for the purpose of removing dirt, gravel, stones, etc., from a ditching wheel, and therefore the parts must be made sufficiently heavy to withstand the strains to which they are subjected in such work. Furthermore the conveying apron must be supported by suitable means, as the rollers 16, in order to prevent sagging under heavy loads, and at the pivot portion 55 of my conveyer it is essential that some means as the guiding rollers or disks 15, be provided for the same purpose.

A most serious difficulty in all conveyers for ditching machines is met with in the tendency of the dirt, gravel, or stones, to get into the sprocket gearing, and either cause a break in the machinery or a stoppage of the machine. My bracket 23, three sided frame 24, and flexible sides 25, passing down and

overlapping the conveying apron furnishes a means which actual use, on a large scale has demonstrated to be amply sufficient to prevent these annoying accidents; while at the same time, a sliding connection between said sides 25 and said conveying apron 26 is provided; which connection allows the apron to perform its functions the same as if said sides 25 did not exist. It will be observed further more, that the same characteristics are not required in any kind of conveyer other than that above set forth, nor are they to be found so far as I am aware in any conveyer, whatever, prior to my invention.

Having thus described the invention, what I claim is:

1. The combination with a conveyer for excavating machines comprising two frame members pivotally connected together having guiding rollers 16 journaled in said frame members, and provided with guiding disks 15 journaled in the pivotal portion of said frame, of a hopper disposed at the receiving end of the conveyer comprising a suitably-supported three sided frame provided with depending flexible means disposed substantially in engagement with the conveyer apron, substantially as described.

2. The combination with a conveyer frame for excavating machines comprising two frame members pivotally connected together having guiding rollers 16 journaled in said frame members and provided with guiding disks 15, journaled in the pivotal portion of said frame, of a hopper disposed at the receiving end of said conveyer frame, and comprising a three sided suitably-supported frame provided with depending sides projecting into engagement with the apron of said conveyer, and composed of canvas or similar material, substantially as described.

3. The combination of a conveyer frame for ditching machines comprising two frame members hingedly connected together, one of said frame members being adapted to be rigidly secured to the machine, of guiding rollers 16 journaled within said frame members, guiding disks 15 journaled in said hinged portion, means for driving an endless conveyer apron over said rollers, a hopper carried by said rigid frame member and comprising a suitably supported three sided frame provided with depending sides of canvas or similar material projecting into engagement with the conveyer apron, and guiding gearing located under said sides, substantially as described.

4. A conveyer support for excavating machines containing as elements a two-part frame member provided with projecting bearing arms at one end thereof, a shaft passing through said bearings pivotally connecting said frame member, rotatably mounted wheels on said shaft, rotatable end shafts

and wheels carried thereby, rollers journaled within said frame, idle sprocket wheels disposed along said frame, driving means carried by said end shafts, said sprockets, rollers and wheels coöperating to movably support an endless conveyer apron, brackets 23 supported on said frame, a three sided frame 24 supported on said brackets and flexible sides 25 supported by said three sided frame

and reaching down and slidingly engaging 10 said apron, substantially as described.

In testimony whereof, I affix my signature in presence of two witnesses.
